APPARATUS FOR TREATING WELLS

Leonard C. Chamberlain and Ormond E. Barstow,
Midland, Mich., assignors to The Dow Chemical
Company, Midland, Mich., a corporation of
Michigan

Application August 28, 1940, Serial No. 354,507

3 Claims. (Cl. 166—1)

The invention relates to a apparatus for treating wells, such as oil, gas, brine and water wells, whereby a fluid treating agent may be simultaneously introduced into at least two zones, while one zone is sealed from the other zone in such a manner that the fluid in the well bore about to enter one zone is maintained out of contact with the fluid entering the other zone. It more particularly concerns a method of treating wells whereby the fluid treating agent being simultaneously introduced into at least two zones may be controlled in such a manner that the rate of flow to each zone may be varied at will during the course of a treatment.

The bore of a well oftentimes penetrates more than one zone, and it is usually desirable when treating such wells with a fluid treating agent, such as, for example, an acid, to control the rate at which the treating agent is entering each zone during the course of the treatment. For example, it is desirable to vary the rate of flow of acid being directed to each zone during the course of a treatment, because one zone may become highly porous during the course of the treatment and absorb practically all of the treating agent with the result that waste of the treating fluid occurs and the most desirable results as regards the most effective increase in permeability are not obtained. It is further desirable when treating such wells that the introduction of fluid agent into each zone or stratum takes place simultaneously, in order to avoid the necessity of carrying out a separate treatment of each zone.

The term "zone," used herein and in the appended claims, refers to separately defined strata, as well as portions or sections of the same formation or stratum.

It is, therefore, the principal object of the invention to provide a method and apparatus whereby a fluid treating agent may be simultaneously introduced into at least two strata or zones penetrated by the bore of a well and at the same time to provide a means whereby the rate of flow of fluid may be varied during the course of the treatment so that the fluid may be caused to enter a selected zone at a more rapid or a slower rate.

Still other objects and advantages will be apparent as the description of the invention proceeds.

The invention then resides in the method and apparatus hereinafter more fully described and particularly pointed out in the claims, the following description and accompanying drawing

setting forth in detail a mode of carrying out the invention, such mode illustrating, however, but one of the various ways in which the invention may be put into operation.

5 In the accompanying drawing the single figure is a fragmentary view partly in vertical cross section of a well bore showing an embodiment of the invention.

As shown, the well bore is lined with iron or 10 steel pipe 1 down to a point 2 where it is cemented in place by means of cement 3. The lower portion of the well bore penetrates a productive stratum 4, an impervious stratum 5, and ends in a second productive stratum 6. The conventional well tubing 7 is shown extending into the well and is attached at its lower end to conduit 8 by means of a conventional coupling or collar 9. The conduit 8 is internally and externally threaded at its lower end. The externally threaded portion engages a second conduit 10, while a guide shoe 11 engages the internally threaded end. The second conduit 10 is provided with slotted port 12 and is also externally and internally threaded at its lower end in a manner similar to that of conduit 8. A tubular member 13 engages the lower end of conduit 10 externally thereof, while a second guide shoe 11 identical with the upper guide shoe 11 externally threaded portion engages the lower end of conduit 10 internally thereof. Tubular member 13 is attached at its lower end to conduit 14 by means 20 of coupling 9. The conduit 14 supports packer 15 of conventional design shown seated against impervious stratum 5. Below the packing element 15, the conduit 14 extends into the well and is provided with a port 16 through which fluid flows from the interior of the conduit 14. The lower end of conduit 14 is shown sealed off by cap member 17, which is seated against the bottom 25 of the well bore. The guide shoes 11 engaging the lower ends of conduits 8 and 10 are provided with centrally disposed openings 18 which flare out at the upper ends to provide a beveled surface 19. The lower ends of guide shoes 11 are provided with threaded shoulder portions 20. Cap members 21 with centrally disposed openings 26 engage the shoulders 20 and hold packing 22 against the shoulders 20. The beveled surface 19 on guide shoes 11 allows the conduit 23 to readily engage the centrally disposed openings in guide shoes 11 while the packing gland formed at the lower end of the guide shoes allows conduit 23 to be raised and lowered in sliding sealing relationship through the guide shoes. The conduit 23 is provided with a series of spaced restricted ports

24 about its lower end, while at a point adjacent its upper end relatively large slotted ports 25 provide a means for fluid entry into conduit 23. Conduit 23 is shown attached to a weight 26 by means of coupling member 27. The weight 26 is in turn provided with a ring 28 to which a wire line 29 is secured. The wire line extends to the earth's surface and serves as a means whereby the conduit 23 may be raised and lowered through the guide shoes 11.

The operation of the method will be best understood from the following description, wherein the apparatus illustrated is employed to carry out the simultaneous injection of acid into each of two productive strata 4 and 6. With the apparatus positioned as shown in the drawing, a quantity of acid is started into the well through tubing 1. The acid flows downwardly and enters the slotted ports 25 provided in conduit 23. The acid then discharges through the ports 24 in conduit 23, a portion thereof being confined to the space between the two guide shoes 11, while the remainder discharges into conduit 14 and flows downwardly through packing element 15 to the lower portion of the well. The acid discharging from the port 24 located between the guide shoes flows outwardly through port 12 into the well bore adjacent productive stratum 4, while the acid flowing downwardly through the packer discharges through port 16 into the well bore adjacent productive stratum 6. As the treatment continues, a quantity of oil or the like may be introduced into the annular space between the tubing and the casing to control the level to which the acid may rise in the well bore. At any time during the treatment when it is desired to change the rate of flow of acid reagent to one stratum, it is only necessary to raise or lower the wire line 29, thus allowing more or less of the restricted openings 24 in conduit 23 to communicate with the desired stratum. In this manner, the ratio of rates of flow can be varied widely during the course of the treatment.

In the case of an acid treatment, it is usually desirable to inject a larger portion of the acid into the zone having the highest resistance to the flow of fluids. By raising and lowering conduit 23 so as to expose most of the restricted ports 25 to first one zone and then the other, the section requiring the application of the highest pressure to force fluid thereinto at a given rate is readily determined at any time during the treatment. The conduit 23 may then be positioned so as to direct a larger portion of the acid to the zone having the highest resistance to flow.

The method will be found to have most general use in connection with an acid treatment wherein a solution of hydrochloric or other acid is introduced into the formation to bring about solution of the earth or rock formation and thus an increase in size of the flow channels through which the desired mineral fluid flows to the well. In such treatments it will usually be found preferable to employ an aqueous solution of hydrochloric acid of from 5 to 25 per cent concentration. If desired, such an acid may be inhibited against corrosive attack upon iron or steel in the manner taught in U. S. Patent No. 1,877,504.

Although the method has been described with particular reference to an acid treatment, it is to be understood that any fluid treating agent may be introduced in accordance with the method

of the invention. Examples of such treating agents are paraffin solvents, liquid sealing agents, and the like.

In the above manner, a fluid treating agent may be simultaneously introduced into two or more strata or zones of production and at the same time the rate of flow of fluid to each zone is susceptible of control at all times during the treatment.

10 We claim:

1. In a well treating device for the simultaneous injection of a fluid agent into at least two zones penetrated by the bore of a well, the combination which includes a conduit having spaced openings therein, sealing means surrounding said conduit at a point between the openings adapted to seal the annular space between the conduit and the well bore, a tubular element disposed within the conduit having a relatively large fluid entry port adjacent the upper end and restricted fluid discharge ports adjacent the lower end, and means associated with the tubular element adapted to allow said element to be raised and lowered in the conduit, sealing means in the 15 conduit surrounding the tubular element at points both above and below the upper spaced opening in the conduit, said sealing means being adapted to seal the annular space between the conduit and the tubular element and to allow the latter to be raised and lowered in sliding sealing relationship.

2. In a well treating device for the simultaneous injection of a fluid agent into at least two zones penetrated by the bore of a well, the combination which includes a conduit having spaced openings therein, sealing means surrounding said conduit at a point between the openings adapted to seal the annular space between the conduit and the well bore, a weighted wire 35 line operated tubular element disposed in the conduit and having a relatively large fluid entry port adjacent the upper end and restricted fluid discharge ports adjacent the lower end, and sealing means in the conduit surrounding the wire line operated tubular element at points both above and below the upper spaced opening in the conduit, said sealing means being adapted to seal the annular space between the conduit and the wire line operated tubular element and 40 to allow the latter to be raised and lowered in sliding sealing relationship.

3. In a well treating device for the simultaneous injection of a fluid agent into at least two zones penetrated by the bore of a well, the combination which includes a conduit having spaced openings therein, sealing means surrounding said conduit at a point between the openings adapted to seal the annular space between the conduit and the well bore, a tubular element disposed in said conduit having a relatively large fluid entry port adjacent the upper end thereof and restricted fluid discharge ports adjacent the lower end, sealing means surrounding the tubular element at points both above and below the upper opening in said conduit, said sealing means being adapted to seal the annular space between the conduit and the tubular element and to allow the latter to be raised and lowered in sliding sealing relationship and a wire line attached to said tubular element for raising and lowering said tubular element.
